UNITED STATES PATENT OFFICE.

CARL H. SCHMIDGALL, OF PEORIA, ILLINOIS.

BORING-TOOL.

1,297,740.

Specification of Letters Patent. Patented Mar. 18, 1919.

Application filed July 16, 1917. Serial No. 181,443.

To all whom it may concern:

Be it known that I, CARL H. SCHMIDGALL, citizen of the United States, residing at Peoria, in the county of Peoria and State of Illinois, have invented certain new and useful Improvements in Boring-Tools; and I do hereby declare that the following is a full, clear, and exact description of the invention, which will enable others skilled in the art 10 to which it appertains to make and use the same.

This invention relates to a tool for boring holes whose walls describe a polygon, or whose walls may describe curves, adapted 15 for boring in wood or metal.

The primary object of my invention is the provision of a tool which by its form will at one operation bore a hole of a predetermined form.

20 Other objects and advantages will appear in the following specification besides certain details of construction all of which will appear herein aided by the accompanying drawing which shows one of the embodiments of my invention, it being understood that changes may be made that will lie within the meaning and intent of the invention and such as will fall within the scope of the appended claims.

30 Figure 1 is an elevation of the complete tool.

Fig. 2 is a longitudinal section of the same.

Fig. 3 shows the tool as seen from the top.

35 Figs. 4 and 5 are plans of modified forms of the tool seen in plan.

The body of the tool preferably comprising a handle portion 1 having at one end a cavity 2 with which communicates a longitudinal bore 3. Within the bore is designed 40 to rotate a shaft 4 which preferably extends from one end of said body, and it is provided within the described cavity 2 with a miter-gear 5 suitably affixed to it.

In the first three figures that portion of 45 the body having the cavity 2 takes a square form as viewed in plan, Fig. 3, and in each of the walls created by said cavity is a bore 6, Fig. 2, each of which may receive a hardened bushing 7 to form a bearing for short shafts 8 whose axes are perpendicular to the axis of the shaft 4. Each is provided within the cavity 2 with a pinion-gear 9 arranged to mesh with the described gear 5.

50 10 is a cap or closure for the cavity 2 se-

cured to the end of the body by any suitable means such for example as screws 11, Figs. 1 and 3, said cap or closure including within the cavity an extension 12. This said extension may answer two purposes—that of providing a bearing for the described extension 60 of the shaft 4, and also for the inner ends of the described short shafts 8. The latter are slightly reduced in diameter at their inner ends and rotate within sockets 13 in the said extension 12 and are threaded to 65 receive their respective pinion-gears 9.

Adjacent the described threads each shaft is furnished with an enlarged portion 14 adapted to have a running fit in the described hardened bushing 7. Outward from the enlarged portion the shaft is threaded to screw into a correspondingly threaded bore 15 of a cutter 16 having in this instance the form of a cone. The described cutters are fluted as clearly shown in Fig. 1, the cutting edges 70 of each of the cutters being so disposed with regard to their direction of rotation as to properly engage the work.

In assembling the tool after the shaft 4 and its gear 5 have been placed in position, 80 the pinion gears 9 are dropped into the cavity 2 and the cap or plate 10 secured in position. The short shafts 8, each of which is provided with a screw-driver slot 17 at its outer end, are then inserted through the 85 bushing 7, and screwed into the pinion-gears 9 which being in mesh with the miter-gear 5 can be held from rotating at this time by grasping and preventing the shaft 4 from 90 rotating. As this operation is performed the inner ends of the shafts are projected into the sockets 13 which form bearings for the same.

After the shafts are screwed "home" the 95 cutters are run upon the threaded outer ends of the shafts and the tool is ready for work.

The enlarged portion 14 of each short shaft 8 serves as an abutment for the pinion-gear 9 at one side and the cutter 16 at the other, there being just sufficient clearance so 100 that the rotating unit made up of the shaft, gear and cutter will rotate without binding.

It is now seen that each shaft 8 has two bearings, one within the extension 12 and the other within the bushings 7, so that they 105 rotate freely and without undue wear and readily take the lateral pressure imposed by the cutters when at work without undue fric-

tion or binding. The said bushings 7 take the wear of the shafts 8 and when worn may be replaced by new ones, the shafts themselves being also replaced when they become worn. Likewise the cap 10 may be replaced for like reason. By this arrangement the body 1 is never damaged or rendered unfit for use by wearing and need never be removed, all parts subject to wear being renewable.

The shaft 4 may terminate within the extension 12 or it may extend through the cap or closure 10 as shown and may receive a sleeve 18 or other suitable part which may be suitably secured to it, said sleeve forming a socket for the shank of an auger-bit 19, boring tool, or a drill. 20 is a collar suitably secured on the shaft 4 and spaced from the handle-portion. 21, 21 indicate two collars interposed between said collar 20 and said handle-portion. 22 indicates a series of balls interposed between the collars 21, and 23 is a ball-retainer. Since the applied pressure is upon the shaft 4, when the cutters 16 are at work, the collars 21 and balls 22 form thrust bearings which permit the gears 5 and 9 to work freely. When the boring element 19 only is at work prior to the engagement of the cutters 16 with the work the thrust bearings are of course not in use since at that time the shaft 4 and element 19 are as a single part.

24 is an arm of any suitable form secured upon the handle portion 1 by which to support the tool in an upright position during operation.

In the form shown in the first three figures wherein, as before stated, the body is square in form, by means of a drill, bit, or other tool, a hole is first drilled in the material in which the hole is to be formed, the diameter of the said drill, bit, or other tool being substantially equal to or slightly larger than the diagonal measurement of said body, as indicated by the circle shown by a broken line *a* in Fig. 3.

It is observed that each cutter has a diameter at its base about equal to the width of each face of the body opposite which it lies so that a line drawn between the apices of any two adjacent cutters will just pass the corner of the body and that, as in the figure last referred to, a perfectly square hole will be cut in the work indicated at *X*.

55 In Fig. 4 the body indicated at A takes the form of an equi-lateral triangle having on each of its faces a cutter B corresponding to 16 in the other figures, though of necessarily slightly different form, that is, having 60 steeper sides to form acute corners instead of right angles as used in cutting a square hole.

In Fig. 4 the dotted line B' indicates the size of the bore to be made by the auger-bit and in Fig. 5 the dotted line F' indicates 65 the size of hole for the particular size of tool

in that figure, it being observed that in each case the hole to be bored is of a diameter large enough to receive the body of the tool, the cutters clearing out the material necessary for the hole of the required form.

70 In Fig. 5 the body represented at C is in the form of a hexagon from each of whose faces projects a cutter D whose edges meet at the corners of the hexagon. This structure makes a hexagonal hole E in the work indicated at F.

75 My tool may be furnished with the auger-bit 19 described but this may not be used in conjunction, since a separate auger-bit may be employed to bore a hole to be afterward shaped or worked out by the cutters. The cutters 16 operate in either metal or wood and when working in the latter they carry up, by means of the cutting edges thereof, the chips constantly forced up by the bit 19. 80 In working in metal, of course, a suitable drill replaces the bit.

85 The tool is not confined to making openings having flat or straight walls since the cutters may have curved faces whereby they 90 may be adapted for cutting holes having curved walls for example.

95 The tool is of great value in making wrenches commercially, the square, hexagonal or octagonal holes, as the case may be, being formed rapidly and accurately. It is also of value in making holes of various shapes for special purposes. The working parts of my tool are thoroughly protected from the cuttings of the material in that 100 the closure 10 tightly covers the recess 2. The shafts 14 are the only portions extending from the body but as these rotate in closed bearings the material cannot enter at those points.

105 The advantage in mounting the shafts so as to have two bearing points admits of the gears 9 lying between them. There can be no lateral strains, therefore, from the gears upon the shafts thus supported such as to 110 cause binding or springing thereof. Furthermore, the cutters which would under work naturally set up lateral strains upon the shafts cannot cause the latter to bind in their bearings.

115 It is preferred to screw the gears 9 upon the shafts since by that means there is no danger of the said shafts slipping out of the gears, it being understood that when the closure 10 is put in position, the shafts must 120 necessarily be introduced into their respective gears. Since the direction of rotation of the gears is clock-wise they will tend to tighten upon the shafts due to their threaded engagement therewith.

125 As previously stated, changes may be made that may suggest themselves to the practical person since it is not my wish to be confined to what is described and shown, which is merely the preferred way.

Having thus described my invention, I claim:—

1. A boring tool comprising, in combination, a body including a bore terminating in a recess, a drive shaft in said bore, a gear on said shaft within the recess, a part extending into the recess spaced from the walls thereof, a series of shafts having their bearings in the body and said part, a gear on each shaft of the series between the walls of the recess and the said part and in mesh with the first named gear, and a cutter on each shaft outside the body.
2. A boring tool of the type described including in combination, a body having a bore, and a recess at one end communicating with the bore, a shaft journaled in said

bore including a gear lying in said recess, a closure for the recess including an extension lying within the said recess spaced from 20 its walls, a series of shafts journaled each at one end in the extension, and also journaled near its other extremity in the wall of the body, a gear on each shaft of the series between the extension and said wall and rotatable with said shaft, and a conically formed cutter secured on the extremity of each shaft outside said body.

In testimony whereof I affix my signature, in presence of two witnesses.

CARL H. SCHMIDGALL.
